UNITED STATES PATENT OFFICE

KENNETH HOWIE, OF NORRISTOWN, PENNSYLVANIA, ASSIGNOR TO WILDMAN MFG. CO.,
OF NORRISTOWN, PENNSYLVANIA, A CORPORATION OF PENNSYLVANIA

REVERSIBLE PLATING YARN FEED FOR CIRCULAR KNITTING MACHINES

Application filed February 6, 1930. Serial No. 426,288.

My present invention relates to improvements in circular knitting machines and more particularly it relates to a reversible plating yarn feed for such machines.

An object of the invention is the provision of a mechanism which will reverse the yarn feed fingers so as to reverse the yarn in the plating effect in the fabric in an effective and accurate manner and with simplicity and sturdiness of construction.

Other objects will appear hereinafter.

The invention consists in the features, combination, and arrangement of parts hereinafter described and particularly pointed out in the claims.

In the drawings,

Fig. 1 is a plan view of the mechanism embodying my invention;

Fig. 2 is an elevation of the yarn guide portion of the mechanism;

Fig. 3 is sectional view taken substantially on line 3—3 of Fig. 1;

Fig. 4 is a fragmentary detail rear view of a yarn feed finger showing the flattened portion at the bend in the finger.

In the drawings, 1 represents the sinker to the feed point or notch 2 of which is fed the yarn from yarn feed fingers 3 and 4.

The yarn feed fingers are mounted in guide plate 5 for vertical movement therein, the guide plate being secured to the yarn guide bracket 6 by screw 7, the yarn guide bracket 6 being in turn adjustably secured to the cam ring 8 by clamping screw 9 in slot 53.

The yarn guide bracket supports the yarn guide arm 10 having yarn guide apertures 11 and 12 through which the yarn 13 and 14 passes respectively to yarn feed fingers 3 and 4.

The yarn feed fingers 3 and 4 comprise angularly bent tubes mounted for longitudinal sliding movement in the guide plate 5. The tubes with their longitudinal major portions slidable substantially vertically in the

guide plate 5 and their laterally turned lower ends for delivering the yarn in a substantially horizontal direction across the feed point or notch 2 of the sinker 1, are linked together by means of link 15. Link 15 so connects the movable feed fingers that when one is up the other is down and thus one yarn is fed above the other at the feed point. The movable feed fingers are arranged so that their horizontal delivery portions are out of line and may pass each other, since as shown the mouths of the tubular fingers are approximately one above the other.

The link 15 is pivotally mounted on the guide plate 5 at 28 and pivotally engages at its ends with pins 16 and 17 extending through slots 26 and 27 and fixedly mounted on the feed fingers 3 and 4 as by collars 22 and 23 having set screws 24. The upper end of feed finger 3 is provided with a projection 18 providing a shoulder upon which bears the free end of arm 19 which is pivotally mounted at its opposite end upon the yarn guide bracket as shown at 20. The feed finger 3 is urged upwardly by spring 21 which extends between collar 22 and the lower guide 25 of the guide plate 5. The feed fingers 3 and 4 project through aligning bores in upper and lower guide portions 29 and 25. The projection 18 is preferably in the form of an adjustable collar having a set screw 30 for fixing it to the tubular feed finger 3. A member 31 similar to member 18 is secured by set screw 32 to the feed finger 4 near its upper end to provide an adjustable stop for limiting downward movement of the feed finger 4 and consequently limiting upward movement of feed finger 3.

The presser arm 19 is extended beyond its pivotal connection 20 to the yarn guide bracket 6, and this extension 33 is engaged by arm 34 of bell crank lever 35 pivotally connected to the yarn guide bracket at 36. The other arm 37 of the bell crank 35 extends across the row of needles 38 and preferably carries

at its free end a roller 39 adapted to ride upon the surface of cam wheel 40.

The cam wheel 40 is adjustably mounted for rotary movement upon a forked supporting arm 41 fixed at 42 to a bracket 43 adjustably mounted upon the cam ring 8 at 44. The cam wheel is provided with peripheral teeth 45 adapted to engage the needles in needle row 38. As indicated by the arrow the needle row 38 may rotate with respect to the cam ring 8, and the cam wheel 40 is rotated by reason of the engagement of the needles with the teeth of the cam wheel.

A two part adjustable cam 46, 47 is mounted upon the wheel 40, the parts 46 and 47 being arcuate in shape and having their faces in contact. Each part has a flat portion 48 and the inclined cam ends 49 are at opposite extremities of the two part cam. The part 20 46 is fixed upon the wheel 40 while the part 47 is mounted for arcuate adjustment relative thereto, to increase or decrease the length of the two part cam. A slot 50 in part 47 cooperates with a clamp screw 51 to this end. 25 Even at the minimum adjustment the inclined ends 49 of each part projects beyond the abrupt end of the other part, to provide cam inclines for gradually elevating and lowering the roller 39 of arm 37 of the bell crank.

30 In the operation of the device, as the needle row 38 rotates with respect to cam ring 8, the cam wheel 40 is rotated. With the parts in the position shown in Fig. 1, the roller 39 is engaging the flat surface of the wheel 40 and the tubular yarn feed fingers and associated parts are in the position shown in Figs. 2 and 3, with the arm 19 exerting no force upon the feed finger 3 and the spring 21 holding the finger 3 up and the finger 4 down, 35 which causes the yarn of finger 3 to be fed to the sinker 1 above the yarn delivered by feed finger 4.

Upon rotation of the wheel 40 from the position shown in Fig. 1, the cam 46, 47 will 45 engage the roller 39 and lift the arm 37 of bell crank 35 which will cause the other arm 34 of the bell crank lever to lift the extension 33 of presser arm 19. This will depress the arm 19 about pivot 20 and the feed finger 3 50 will be pushed down and held so during the passage of the cam 46, 47 beneath the roller 39. The feed finger 4 will be raised upon depression of finger 3 and their delivery ends will pass each other and will be reversed in position with the feed finger 4 delivering its yarn above the yarn delivered by the feed finger 3 thus reversing the plating effect in the knitted fabric.

The extent of the adjustment of cam part 55 47 with respect to the part 46 determines the length of time that the feed fingers are held in reversed position and the extent of the reverse plating effect in the fabric.

The roller 39 is of sufficient width to span the width of both parts 46 and 47 and hence

will ride up the incline of one and will ride down the incline of the other.

I do not wish to limit the invention to any certain direction of rotation nor to rotation of the needle row with respect to the cam ring 8, as it is apparent that the direction of rotation may be reversed and the cam ring 8 may be rotated with respect to the needle row without departing from the scope of the invention within which modifications may be made.

I claim:

1. A reverse plating yarn feed mechanism for circular spring needle knitting machines having sinkers and having a cam ring and a needle row adapted for relative movement, yarn feed fingers mounted on the ring and movable with respect to the sinkers, a cam wheel having teeth engaging the backs of the needles and rotatably mounted on said ring, said cam wheel rotating in a substantially horizontal plane and having a cam surface on its upper face and operating connections between the cam and the fingers comprising a bell crank lever pivotally supported by the ring, one arm of said bell crank riding on the cam surface, an arm pivotally mounted on said ring and engaging one of said feed fingers, said arm having an extension beyond its pivot engaged by the other arm of the bell crank, link means interconnecting said fingers so that movement of the one moves the other in the opposite direction, and a spring urging the presser engaged finger upwardly.

2. In a reverse plating yarn feed mechanism for circular knitting machines having a cam ring and a needle row adapted for relative movement, the combination of a bracket mounted on the ring, a planetary wheel having a cam surface mounted upon said bracket and having toothed engagement with the backs of the needles to be rotated thereby, yarn feed fingers, a guide plate in which said fingers are movably mounted, a yarn guide bracket to which said plate is secured, an arm pivoted to said bracket and engaging a yarn feed finger to move the same, a bell crank lever pivoted to said yarn guide bracket, one arm of said bell crank operating said pivoted arm, and the other arm of said bell crank riding on said cam surface, a link connecting said yarn feed fingers so that they move oppositely, and a spring urging the said yarn feed finger against the presser arm.

3. In a reverse plating yarn feed mechanism for circular knitting machines having a cam ring and needle row adapted for relative movement, a planetary wheel having a cam surface and peripheral teeth and carried by said ring and having planetary toothed engagement with the needles of the needle row to be rotated thereby, said cam surface comprising a fixed arcuate raised

portion and a movable arcuate raised portion adapted for arcuate adjustment relative to the fixed portion to increase or decrease the extent of the combined raised portions.

- 5 4. A reverse plating yarn feed mechanism for circular spring needle knitting machines having sinkers and having a cam ring and a needle row adapted for relative movement, 10 yarn feed fingers movably mounted on the ring and with respect to the sinkers, a cam wheel having peripheral teeth engaging the needles of the row and rotatably mounted on said ring, and means in engagement with 15 said feed fingers and controlled by said cam to move the fingers relative to each other, said cam wheel having an annular cam surface the extent of which is adjustable, said cam surface being provided by a fixed raised 20 portion and a movable raised portion, and a clamp for holding the movable portion in adjusted position relative to the fixed part to increase or decrease the length of the combined raised portions.

- 25 5. In a reverse plating yarn feed mechanism for circular spring needle knitting machines having sinkers and having a cam ring and a needle row adapted for relative movement, a yarn guide bracket adjustably mounted upon the ring, a guide plate secured to 30 said bracket, a pair of yarn feed fingers slidably mounted in said guide plate, link means interconnecting the movable fingers so that movement of one moves the other in the opposite direction, said feed fingers having laterally turned lower ends mounted to pass each other to position one above the other to feed the yarn at different levels to the sinker to reverse the plating effect in the fabric, and 35 40 means controlled by said relative movement to position the yarn feed fingers in reversible relation one up and one down.

6. In a reverse plating yarn feed mechanism for circular spring needle knitting machines having a row of sinkers and having a cam ring and a needle row adapted for relative movement, yarn feed fingers supported upon the ring for movement to and from the feed point of the sinkers, a link connecting 50 said fingers so that when one is up the other is down, and means controlled by the said relative movement to position the fingers in one offset relation or the other, said means including a planetary wheel having a cam 55 surface and carried by said ring and having planetary toothed engagement with the needles of the needle row and rotated thereby, and lever means carried by said ring and in engagement with said fingers and said cam 60 to determine the offset position of the fingers according to the cam surface.

7. A reverse plating attachment for spring needle knitting machines comprising the toothed cam wheel driven by engagement 65 with the backs of the spring needles, said

toothed cam wheel being arranged to rotate about a substantially vertical axis within the needle row, yarn fingers arranged to have relative up and down movement to reverse their yarn feeding relations, and means for 70 changing the relative positions of the yarn fingers, said yarn fingers having laterally turned lower ends to the feed the yarns horizontally to the sinker, said laterally turned fingers being mounted to pass each other to 75 position either above the other.

In testimony whereof, I affix my signature.

KENNETH HOWIE.
